PARTICULATE MATERIAL DISTRIBUTOR FOR UTILIZATION ON OIL POLLUTION SPILLS

Ralph E. Lingert and Richard E. Keyes, Cincinnati, Ohio, assignors to The Finn Equipment Company, Cincinnati, Ohio

Filed Aug. 27, 1970, Ser. No. 24,717

Term of patent 14 years

Int. Cl. D15—03, 99

U.S. Cl. D55—1

FIG-2

FIG. 1 is a perspective view of the rear and one side of a particulate material distributor for utilization on oil pollution spills, showing our new design.

FIG. 2 is a perspective view of the front and the other side thereof.

We claim:

The ornamental design for a particulate material distributor for utilization on oil pollution spills, as shown and described.
